UNITED STATES PATENT OFFICE.

HARRY C. DOAN AND CLIFFORD J. MARSON, OF RICHMOND, INDIANA.

DESIGN FOR A PISTON-RING.

57,319.

Specification for Design.

Patented Mar. 15, 1921.

Application filed July 26, 1920. Serial No. 399,195. Term of patent 14 years.

To all whom it may concern:

Be it known that we, HARRY C. DOAN and CLIFFORD J. MARSON, both citizens of the United States, residing in the city of Richmond, in the county of Wayne, State of Indiana, have invented a new, original, and ornamental Design for a Piston-Ring, of which the following is a specification, reference being had to the accompanying drawing, forming a part thereof, in which—

Figure 1 is a perspective view of a piston ring showing our new design.

Fig. 2 is also a perspective view of the same but showing the parts thereof not shown in Fig. 1.

Fig. 3 is a central cross section of a piston ring showing our new design in cross section.

Fig. 4 is a detail cross section of a piston ring also showing our design on a greatly enlarged scale.

Having now fully shown our invention, what we claim and desire to secure by Letters Patent of the United States, is:

The ornamental design for a piston ring, substantially as shown.

In testimony whereof we have hereunto subscribed our names to this specification in the presence of two subscribing witnesses.

HARRY C. DOAN.
CLIFFORD J. MARSON.
